UNITED STATES PATENT OFFICE.

ROBERT WEIR, OF MUSKEGON, MICHIGAN.

LOG-CANTER.

SPECIFICATION forming part of Letters Patent No. 233,306, dated October 12, 1880.

Application filed July 2, 1880. (No model.)

To all whom it may concern:

Be it known that I, ROBERT WEIR, residing at Muskegon, in the county of Muskegon and State of Michigan, have invented certain new and useful Improvements in Log-Canters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to an improvement in log-canters, consisting in the attachment of certain devices thereto, by which it is enabled to roll logs from the log-deck of a saw-mill onto the carriage.

In carrying out this invention I affix to the stiles or uprights of the log-canter two brackets. In these brackets a vertical shaft or spindle is journaled, upon which, between the brackets, is secured a double incline. To the top of the spindle is secured a segmental wheel or pulley, through which the spindle, with its inclines, may be partially rotated. When the inclines are in line with the toothed bar which moves the log they act upon its lower end beneath its fulcrum, causing its upper part, which comes in contact with the log, to have a much greater horizontal range of motion than the lower end, enabling it to reach back behind a log on the deck and roll it forward toward the carriage; but when the log is in place upon the head-blocks of the carriage the spindle, with its inclines, is turned to one side, and the canter, uncontrolled by it, performs its usual function of turning the log upon the head-blocks.

To more fully understand its construction and operation, I will now proceed to describe the drawings, in which—

Figure 1 is a side view of a log-canter, with sections of the log-deck and saw-carriage. Fig. 2 is a rear view of the canter and its operative mechanism. Fig. 3 is a horizontal section on the line $x-x$ of Fig. 2.

In Fig. 1, A represents the log-deck, which is preferably constructed with a slight inclination toward the saw-carriage, the logs being prevented, if necessary, from rolling toward the carriage, as they would do if they were perfectly

straight and round, by a chock or other suitable means.

Running upon rails parallel with the edge of the log-deck, and adjacent thereto, is the saw-carriage B, upon which the head-blocks C, that support the logs during the operation of sawing, are placed. Beneath the log-deck are placed the two parallel upright stiles or guides D D, which support the operative mechanism of the canter, and serve as guides for the cross-head E, which has a vertical sliding movement upon them. Pivoted to this cross-head is the toothed bar or canter F, the pivot by which it is attached to the cross-head serving as a fulcrum, upon which the bar oscillates. Secured to the rear of the bar F is a bracket, G, to the outer end of which is attached the rope or chain a , passing over the sheave H to the winding-drum I, which is put in motion by the mechanism commonly employed for that purpose.

The bifurcated brackets J J are attached to the stiles or guide-posts D D, and form a support for the vertical shaft K, which is journaled therein. Upon this shaft, between the brackets, is secured the double incline L, which, when in the position shown in Fig. 1, forms a guide upon which the friction-wheel b, journaled in bracket M, secured to the lower end of the toothed bar F, runs. It will be evident that as this bearing is beneath the pivotal point or fulcrum upon which the bar oscillates, as the bar rises, its upper end will be thrown back until the friction-roller b reaches the apex of the incline, when its movement will be reversed, and as it continues to rise its upper end will move forward toward the saw-carriage, causing the log upon the log-deck to be rolled onto the head-blocks of the carriage.

When it is desired to use the canter simply for turning logs upon the head-blocks the shaft K is turned part way around, which carries the inclines to one side out of the path of the friction-roller b, thus allowing the bar F to move up and down without interference. In order to give this turning motion to the shaft K a peripherally-grooved segmental wheel, N, is secured to the upper end thereof, around which passes the rope d, one end of said rope running over the guide-pulley c and carrying the weight O, while the opposite end passes under the

guide-pulley *e*, and thence up into a convenient position for the operator. It will be apparent that a pull upon the rope will swing around the incline into the position shown in Fig. 1, 5 and when the rope is released it will be drawn by the weight into the position shown in Fig. 3, the extent of its movement in either direction being governed by the stops *h h*, formed upon the segment-wheel, which, as the wheel turns 10 in either direction, comes in contact with the upper bracket, *J*. These devices might be displaced by others having the same function—viz., turning the incline into and out of line with bar *F*—without departing from the spirit 15 of my invention.

I am aware that substantially the same result as that obtained by the use of my apparatus has been accomplished by means of a cam operating upon an inclined plate secured to the 20 toothed bar, in connection with suitably arranged ropes and pulleys; but this I do not claim.

What I claim as my invention is—

1. In combination with the moving bar of 25 an apparatus for canting logs, the shaft *K* and double incline *L*, mounted in brackets *J J*, and the means described for imparting to said shaft and incline a semi-rotating or swinging movement, substantially as specified.
2. In an apparatus for canting logs, the 30 toothed bar *F*, provided with bracket *M* and

friction-roll *b*, in combination with the swinging double incline *L*, for the purpose of imparting an oscillatory movement to said bar, substantially as described. 35

3. In combination with the moving bar of an apparatus for canting logs, the shaft *K* and double incline *L*, mounted in brackets *J J*, the segment-wheel *N*, pulleys *c e*, and rope *d*, having weight *O*, for imparting a swinging movement to said shaft and incline and an oscillatory movement to the bar, substantially as set forth. 40

4. In an apparatus for canting logs, the combination of the toothed bar *F*, pivoted to the 45 sliding cross-head *E*, between the upright guides *D D*, and provided below its fulcrum with the bracket *M* and friction-roll *b*, the shaft *K*, and double incline *L*, mounted in brackets *J J*, the segment-wheel *N*, pulleys *c e*, and weighted rope *d*, all constructed and arranged for the purpose of imparting an oscillatory movement to said bar, or leaving it free to move in a vertical direction, substantially as shown 50 and described. 55

In testimony whereof I affix my signature in presence of two witnesses.

ROBERT WEIR.
